UNITED STATES PATENT OFFICE.

DOUGLAS W. FRANCHOT, OF TULSA, OKLAHOMA.

SINGLE-TRIGGER MECHANISM FOR MULTIPLE-BARRELED GUNS.

Application filed August 13, 1926. Serial No. 129,049.

My invention relates to improvements in guns and more particularly to the firing mechanism of double barreled shot guns, such as are in general use.

5 Double barreled shot guns are usually provided with a firing mechanism employing two finger triggers, by which the shooter must actuate each trigger separately in order to fire both barrels of the gun. This operation necessitates that the shooter shift his finger from one trigger to the other, to discharge both right and left barrels. Such a required change in position of the hand, when firing both barrels in rapid succession, 15 often destroys the accuracy of the aim of the second shot.

To obviate this disadvantage, and to make possible more rapid discharge of the two barrels of the gun, numerous single trigger firing mechanisms have been proposed. Such devices have, however, been faulty inasmuch as the automatic selector or fire control mechanisms have been unreliable in operation, resulting in both barrels being 25 fired simultaneously, and also, due to the fact that no means has heretofore been provided for locking the automatic fire control mechanism against shifting, to a position to fire the second barrel during the rebound of 30 the gun, which occurs at the time of recoil.

It is therefore the primary object of my invention to eliminate such faults and disadvantages as above pointed out, and to provide a simple, compact and reliable firing 35 mechanism for multiple barreled guns employing a single finger trigger.

A further object of my invention is to provide spring-actuated means co-operating with the finger trigger for positively setting 40 the fire control mechanism to discharge either the right or left barrel of the gun upon actuation of the finger trigger.

A still further object of my invention is to provide reliable safety means co-operating 45 with the fire control mechanism, during recoil of the gun, to positively lock the firing mechanism during rebound in its selected position, and thereafter to automatically release said mechanism to reset in position to 50 fire the second barrel.

Referring now to the accompanying drawings, which are made a part hereof, and on which similar reference characters indicate similar parts:

55 Fig. 1 is a side elevation of a double barreled gun with certain parts of the frame

removed, and the stock shown in section, to illustrate the construction and relation of parts constituting my improved firing mechanism before the gun is cocked. 60

Fig. 2 is a view similar to Fig. 1, of the reverse side of the gun, illustrating the relation of parts when the gun is cocked by opening the breech.

Fig. 3 is an enlarged side elevation, partly 65 in section, of the gun firing mechanism, illustrating the position of parts when slight pressure is exerted on the finger trigger in the act of firing the first barrel of the gun.

Fig. 4 is a view similar to Fig. 3, showing 70 the position of parts at the time the first barrel of the gun is discharged.

Fig. 5 is a view similar to Fig. 3, but in full lines, illustrating the position of parts 75 immediately after the first barrel of the gun has been discharged, and,

Fig. 6 is a view similar to Fig. 5, illustrating the position of parts at the time the second barrel of the gun is fired.

In the drawings, the parts indicated as A 80 represent the usual trigger plate which forms the lower rearward extension of the frame B, C the fore-end iron which is pivoted at D in the frame B, and E and F the left and right barrels of the gun which are 85 carried by the fore-end iron C. All of these parts and such mechanism as is enclosed thereby, and not specifically referred to hereinafter, may be of any well known or approved construction and design, provided 90 they do not depart from the spirit of my invention.

Secured on the trigger plate A, near the forward end thereof, is a trigger block 1, in which the forward end of a finger trigger 95 piece 2 is pivotally mounted on a transverse bolt 3. The trigger piece 2 is formed at its upper rear end with an upwardly pointed extension 4, which, in the normal uncocked position of the parts, as shown in Fig. 1, 100 projects through the trigger slot in the plate A to a point slightly above the upper surface thereof.

Also pivoted on the bolt 3, in the trigger block 1, is a sear lifter arm 5, which extends rearwardly from the block 1 over the upwardly pointed extension 4, of the trigger 105 piece 2. A leaf spring member 6 is formed in piece with, or secured to, the under side of the arm 5 at a point adjacent the forward 110 pivoted end thereof, and extends rearwardly therefrom in normal spaced relation to the

arm, to a point slightly beyond the rear end of the arm. To the rear free end of the arm 5 is pivotally mounted a fire control member 7, which is normally held in a vertical position at substantially right angles to the arm 5 through the action of a wire spring 8.

The fire control member 7 is formed at its lower rear end with a pointed extension 9 which projects downwardly below the arm 5 and to the rear of its pivotal connection 10 with the arm.

In the primary position of the member 7 the pointed lower end 9 is just free of the upper surface of the leaf spring 6. The upper end of the fire control member 7 is formed at its forward edge with an upstanding projection or guard 11, and at its rear edge with a considerably longer projection or stop 12, providing between said projections a movement limiting notch 13.

Immediately to the rear of the fire control member 7 is a block 14 which is bolted to the trigger plate A, and is formed at its upper end with a yoke portion 15 which extends forwardly from the block 14 over the upper end of the fire control member 7.

In the normal uncocked position of parts, the guard projection 11, of the fire control member 7, is positioned immediately below and rearwardly of the forward closed end 16, of the confining slot 17, in the yoke portion 15, and the stop projection 12 extends up into the slot 17.

The confining slot 17, which is provided by the yoke portion 15, extends rearwardly from the closed forward end 16, of the yoke, through the upper end of the block 14, as is clearly shown in Figs. 3 and 4.

To the lower rear end of the block 14 is pivotally mounted a counterweight 18, which is normally held in its rearward position shown in Figs. 1 and 2 by a coiled spring 19 interposed between the block 14 and weight 18 above the pivotal connection 20. The upper end of the counterbalance weight 18 is provided with an aperture 21, in which a rebound delay plunger 22 is slidably mounted.

By reference particularly to Figs. 3 and 4, it will be seen that the rear portion of the plunger 22 is provided with a slot 23, through which a pin 24, secured in the weight 18, extends. A coiled spring 25 is interposed between the forward end of the slot 23 and the pin 24, and serves to hold the plunger normally extended from the forward face of the weight 18. The forward end of the plunger 22 extends into the rear open end of the confining slot 17, and is provided with a slightly enlarged head having a rounded nose 26 which, in the operation of the parts, later to be described, cooperates with the rear edge of the fire control member 7, to lock the member in the

confining slot 17 during the recoil and rebound of the gun.

Secured to one side of the block 14 is a wire spring 27, the free end of which bears on the upper surface of the sear lifter arm 5, to assist the arm in rapidly following the movements of the trigger 2.

Within the frame B is housed the usual hammer mechanism, not shown, which is controlled by a pair of pivoted hammer-holding sears 28 and 29. The sears 28 and 29 extend rearwardly on opposite sides of the trigger block 1 from their pivotal mounting in the frame, and are provided at their rear free ends with inturned trip-projections 30 and 31 respectively, overlying the sear lifter arm 5 as is usual in the construction of certain gun firing mechanisms of this character.

In the operation of my improved single finger trigger firing mechanism for double barreled guns, it will be noted that the in-turned projecting ends 30 and 31 of the hammer-holding sears 28 and 29, occupy different planes relative to each other, above the upper surface of the sear-lifting arm 5. It is obvious therefore that, when the hammers, not shown, of the gun are cocked by breaking the gun as shown in Fig. 2, rocking the sears 28 and 29 on their pivots in the frame B, only the lowermost trip projection 31 will contact with the sear-lifting arm 5, depressing the arm towards the trigger plate A. The arm 5 is thus rocked on its pivot 3 in the trigger block 1, slightly compressing the leaf spring 6, on the upper surface of the trigger plate A, and the upwardly pointed extension 4 of the trigger piece 2.

During this operation the rear pointed lower end 9 of the fire control member 7, is brought into sliding contact with the upper surface of the leaf spring 6, rocking the member 7 forwardly on its eccentric pivot 10, in the free end of the arm 5, to position the guard projection 11 under the forward closed end 16 of the yoke 15.

The gun now being cocked, and the mechanism set to fire the first barrel of the gun, by depressing the finger trigger 2, attention is called to Figs. 3 and 4. It will be noted by reference first to Fig. 3, that, when pressure is first exerted on the finger trigger 2, as indicated by full lines, the upwardly pointed extension 4, of the trigger piece 2, lifts the leaf spring 6 from the trigger plate A, further compressing the spring 6 towards the sear lifter arm 5. Inasmuch as the lower pointed end 9 of the fire control member 7 is eccentric to its pivotal connection 10, with the arm 5, the member 7 is now rocked forward in the confining slot 17, until the stop projector 12 contacts with the closed forward end 16 of the yoke 15.

As pressure on the finger trigger 2 is continued, as indicated by full lines in Fig. 4,

the sear lifter arm 5 is raised, lifting the trip projection 31 of the sear 29 until the hammer, of the first barrel F of the gun, is released to explode the charge. It will also be noted that, as the sear lifter arm 5 is raised by the pressure exerted on the under side of the leaf spring 6, by the trigger projection 4, the selector member 7 is positively held in its forward rocked position while the hammer-holding sear 29 is being raised. The sear lifting arm 5 is thus prevented from being lifted far enough to engage the trip projection 30, of the hammer-holding sear 28, by engagement of the movement limiting notch 13, in the upper end of the fire control member 7, with the forward closed end 16, of the yoke 15. The parts are thus locked by the fire control member 7, making it impossible for the shooter to unintentionally fire both barrels of the gun simultaneously.

When the explosion of the charge in the first barrel occurs, the entire gun is thrown backward in what is termed "the kick or recoil" and involuntarily and beyond the power of concentration of the shooter, the finger of the shooter is released momentarily from the trigger. This interval of time when pressure is released on the finger trigger, which I will call the crisis of the explosion, would permit the leaf spring 6 to spring away from the sear lifter arm 5, releasing tension on the rear pointed end 9 of the fire control member 7, permitting the member 7 to return to its primary position through the action of the wire spring 8 as the arm is forced downward by the wire spring 27.

At the time of recoil there is, however, another action of the gun which is known as the rebound, which action sometimes, during the crisis of the explosion, thus dislodges the notched end of the fire control member 7 from its locking engagement with the closed end 16 of the yoke 15, causing both barrels of the gun to be involuntarily fired.

To provide against any such failure of the parts to remain in selected position during the rebound of the gun, I have provided a safety locking means which co-operates with the fire control member 7 to positively hold the member locked in the confining slot 17 until the crisis of the explosion is over.

By reference particularly to Fig. 4 it will be seen that the parts are in the position which they will assume when the charge in the first barrel F is exploded, and the gun is recoiling. The rounded nose 26 of the delay plunger 22, which is slidably mounted in the pivoted weight 18, is thrown into engagement with the rear edge of the fire control member 7 by the forward rocking movement of the weight 18 and pin 24 compressing the coiled spring 25 against the forward end of the slot 23, in the plunger.

As the arc traversed by the weight 18

during recoil is approximately twice that of the plunger 22, the weight is caused to slide forward on the plunger after the forward movement of the plunger 22 has been arrested by contact of the nose 26 with the member 7. This forward sliding movement of the weight 18 on the plunger 22, rocks the forward end of the plunger downwardly, sliding the rounded nose 26 down the rearwardly inclined edge of the member 7, further compressing the coiled spring 25 against the pin 24.

The plunger 22 is thus held in contact with the member 7 under the tension of the coiled spring 25 during recoil, as shown by full lines in Fig. 4, and also remains in upwardly sliding contact with the member 7 under the tension of the spring 25 during the rearward rocking movement of the weight 18 during rebound, as indicated by dotted lines. The fire control member 7 is thus held up in locked position with the forward closed end 16 of the yoke 15 during the crisis of the explosion when pressure is involuntarily released from the finger trigger as before explained.

Upon the full return of the weight 18 to its primary position under the action of the spring 19, and release of pressure on the finger trigger 2, the parts are returned to their primary positions under the action of the wire springs 8 and 27, as shown in Fig. 5.

The leaf spring 6 now having sprung away from the eccentric pointed end 9 of the fire control member 7, the upstanding guard projection 11 has moved rearwardly under the closed end 16 of the yoke 15, to a position under the retaining slot 15.

The mechanism is now reset to discharge the left or second barrel E of the gun, by again depressing the finger trigger 2.

By reference to Figs. 4 and 5 it will be noted that the inturned trip projection 31 of the hammer-holding sear 29 sprung to a position above the trip projection 30, when releasing the hammer to discharge the first barrel of the gun.

As the finger trigger 2 is depressed to discharge the second barrel of the gun, the first upward movement of the sear lifter arm 5 is unrestricted except for the light tension of the wire spring 27, which tension is not sufficient to cause the upward projection 4 of the trigger piece 2 to deflect the leaf spring 6 to engage the eccentric point 9, of the member 7. The guard projection 11 of the fire control member 7 is thus lifted unobstructed into the confining slot 17 to the rear of the closed end 16 of the yoke 15, permitting the sear lifting arm 5 to come in contact with the trip projection 30, of the hammer-holding sear 28, to discharge the second barrel of the gun, as is illustrated in Fig. 6.

At the time the charge in the second, or left barrel E of the gun is exploded, the safety mechanism, consisting of the pivoted weight 18 and delay plunger 22, is again brought into action, as shown in Fig. 6, but this action on the second shot of course serves no particular function, as the gun shown to illustrate my invention is provided with but two shot barrels.

10 The mechanism shown by the drawings and above described, forms a complete operative gun, all the parts of which co-operate in the operation of the gun to accomplish the purposes described.

15 What I claim is:

1. In a single finger trigger firing mechanism for multiple barreled guns comprising, hammer-holding sears, a finger trigger, a sear lifter, an independently movable fire control means operatively engaged by the trigger and co-operating with said sear lifter for automatically controlling the operation of said sear lifter relative to said sears.

2. In a single finger trigger firing mechanism for multiple barreled guns comprising, hammer-holding sears, a finger trigger, a sear lifter, a fire control member co-operating with said sear lifter, and an independently movable fire control member operating means operatively engaged by said trigger and co-operating with said sear lifter and said fire control member for automatically controlling the operation of said sear lifter relative to said sears.

3. In a single finger trigger firing mechanism for multiple barreled guns comprising, hammer-holding sears, a finger trigger, a sear lifter, a fire control member carried by said sear lifter, and an independently movable fire control member operating means carried by said sear lifter and operatively engaging said finger trigger.

4. In a single finger trigger firing mechanism for multiple barreled guns comprising, hammer-holding sears, a finger trigger, a sear lifter spaced from said finger trigger, a fire control member, and a fire control member operating means operatively engaging said finger trigger and said sear lifter.

5. In a single finger trigger firing mechanism for multiple barreled guns comprising, hammer-holding sears, a finger trigger, a sear lifter spaced from said finger trigger, a fire control member operatively carried by said sear lifter, and a spring member interposed between said sear lifter and said finger trigger.

6. In a single finger trigger firing mechanism for multiple barreled guns comprising, hammer-holding sears, a finger trigger, a spring retracted sear lifter spaced from said finger trigger, and a spring actuated fire control means operatively carried by said sear lifter and engaging said finger trigger.

7. In a single finger trigger firing mechanism for multiple barreled guns comprising, hammer-holding sears, a finger trigger, a sear lifter, a spring member interposed between said sear lifter and said finger trigger, and a fire control member pivotally carried by said sear lifter and normally spaced from said spring member.

8. In a single finger trigger firing mechanism for multiple barreled guns comprising, hammer-holding sears, a finger trigger, a sear lifter, a leaf spring connected to said sear lifter and operatively engaging said finger trigger, a fire control member pivotally mounted on said sear lifter and normally spaced from said leaf spring, and a yoke member cooperating with said fire control member.

9. In a single finger trigger firing mechanism for multiple barreled guns comprising, hammer-holding sears, a finger trigger, a sear lifter movable relative to said finger trigger, a spring member interposed between said sear lifter and said finger trigger, a fire control member eccentrically pivoted in said sear lifter and having its lower end normally spaced from said spring member, and a yoke member co-operating with the upper end of said fire control member.

10. In a single finger trigger firing mechanism for multiple barreled guns comprising, hammer-holding sears, a finger trigger, a sear lifter movable relative to said finger trigger, a fire control member eccentrically pivoted in said sear lifter and having a portion depending below said sear lifter and in normal spaced relation to said leaf spring, said fire control member having a guard projection and a stop projection at its upper end providing a movement limiting notch therebetween, and a fixed yoke member co-operating with the upper end of said fire control member.

11. In a single finger trigger firing mechanism for multiple barreled guns comprising, hammer-holding sears, a finger trigger, a pivoted sear lifter movable relative to said finger trigger, a leaf spring secured to the under side of said sear lifter and operatively engaging said finger trigger, a fire control member having a notched upper end and a stop projection pivotally mounted in said sear lifter, said fire control member having an operating projection eccentric to its pivot in said fire control member and normally spaced from said leaf spring, and a fixed yoke member embracing the stop projection and co-operating with the notched upper end of said fire control member.

12. In a single finger trigger firing mechanism for multiple barreled guns comprising, hammer-holding sears, a pivoted sear lifter, a fire control member pivoted in said sear lifter and having a pointed lower end extending below said sear lifter and eccentrically spaced from said finger trigger.

tric to its pivotal mounting, a yoke member co-operating with said fire control member, a finger trigger, and a leaf spring carried by said sear lifter and interposed between 5 said finger trigger and the lower pointed end of said fire control member.

13. In combination with a multiple barreled gun firing mechanism including a single finger trigger and fire control means, a 10 spring member carried by said fire control means and engaging said finger trigger to control the operation of said fire control means.

14. In combination with a multiple barreled gun firing mechanism including a single finger trigger and a fire control means, a sear lifter movable relative to said finger trigger, and an independently movable fire control operating means interposed between 20 said sear lifter and said finger trigger and co-operating with said fire control means.

15. In combination with a miltiple barreled gun firing mechanism including a single finger trigger and a fire control means, a sear lifter co-operating with said fire control means and movable relative to said finger trigger, and spring means carried by 25 said sear lifter and normally spaced from said fire control means and co-operating with 30 said finger trigger to engage said fire control means when the gun is cocked.

16. In combination with a multiple barreled gun firing mechanism including a single finger trigger and fire control means operated by the finger trigger, recoil operated 35 means co-operating with said fire control means comprising a weight operated delay plunger.

17. In combination with a multiple barreled gun firing mechanism including a single finger trigger and fire control means operated by the finger trigger, recoil operated means co-operating with said fire control means comprising a pivoted weight, a plunger 40 slidably carried by said weight, and a spring interposed between said plunger and weight. 45

18. In combination with a multiple barreled gun firing mechanism including a single firing trigger and a fire control means 50 operated by the finger trigger, a fixed yoke co-operating with said fire control means, and recoil setting means carried by said fixed yoke for locking said fire control means in 55 said yoke during rebound.

19. In combination with a multiple barreled gun firing mechanism including a single finger trigger and a fire control means operated by the finger trigger, a fixed yoke member cooperating with said fire control means, a recoil operated weight carried by 60 said yoke, and a spring pressed member co-operating with said weight and said yoke to lock said fire control means in said yoke during rebound. 65

20. In a single finger trigger firing mechanism for multiple barreled guns comprising a fire control means, a fixed yoke member co-operating with said fire control means, a weight pivotally mounted on said yoke, and a fire control locking member carried by 70 said weight and movable relative to said weight and yoke to engage and lock said fire control means. 75

DOUGLAS W. FRANCHOT.
